WILLIAM N. STACEY, OF SPRINGFIELD, MASSACHUSETTS.

DEVICE FOR BINDING AND HOLDING A SANITARY SLAB, SUCH AS PORCELAIN OR THE LIKE.

1,180,551.

Specification of Letters Patent. Patented Apr. 25, 1916.

Application filed April 8, 1915. Serial No. 20,029.

To all whom it may concern:

Be it known that I, WILLIAM N. STACEY, a citizen of the United States of America, residing at Springfield, in the county of 5 Hampden and State of Massachusetts, have invented new and useful Improvements in Devices for Binding and Holding a Sanitary Slab, such as Porcelain or the like, of which the following is a specification.

10 This invention relates to means and apparatus for binding and holding a sanitary slab, such as porcelain or the like, for a lunchroom chair arm, a table top, and other analogous uses.

15 The object of the invention is to provide improved means for holding and supporting a slab of porcelain or similar material in a rigid and safe manner, said means being so constructed that no crevices, cracks, or holes 20 are present in the top surface of the assembled device into which moisture or foreign matter can enter to render the surface unsanitary.

Another object of the invention is to provide 25 a clamping and holding frame by which a slab of suitable material, such as porcelain, can be rigidly held, and its edges protected without any holes being necessary in the slab, said frame forming together 30 with the slab a perfectly smooth unbroken top surface.

Another object of the invention is to provide 35 a clamping frame for a slab of suitable material, such as porcelain, whereby the slab is clamped around its edge between two separate members of the frame, and the frame is provided with a recess around and extending over the upper edge of the slab which recess may be filled with cement.

40 Other objects of the invention will appear in the detailed description and more particularly in the annexed claim.

Referring to the drawings, Figure 1 is a top view of the frame member assembled 45 as it holds the porcelain slab; Fig. 2 is a bottom view of the same; Fig. 3 is a sectional view taken on the line 3—3 of Fig. 1; Fig. 4 is a detail sectional view taken on the line 4—4 of Fig. 1; and Fig. 5 is a detail sectional view taken on the line 5—5 of Fig. 1.

Referring to Fig. 2, the frame, preferably 50 made of metal, is shown in a form suitable for binding and holding a porcelain slab to be used as the arm of a lunchroom chair.

The bottom frame member is indicated by 1 and comprises a supporting ledge for the porcelain slab, as indicated in Figs. 3, 4, and 5, and depending flanges 8 for connection with the supporting arm of the 60 chair in any suitable manner. Suitable cross members, as indicated in Fig. 2, stiffen and brace the bottom frame member and provide supports on which to conveniently position the flanges 8. The ledge of this 65 bottom frame is provided around its entire edge with an upstanding flange and at intervals with upstanding lugs 5 for a purpose to be described. The top frame member is indicated at 2 in Figs. 1, 3, 4, and 5 and comprises a closed band having a hook-shaped upper extension which overlaps the edge of the porcelain slab 3 and a depending flange 10 extending entirely around the frame. In this upper frame member, there 70 are provided depending lugs 4 which register with the upstanding lugs 5, and the two frame members 1 and 2 are bound together by means of the blind-screws 6 passing through the lugs 4 and 5. The upper 75 hook-shaped portion of the upper frame member is best seen in Figs. 4 and 5, and it will be noticed that a recess is provided between the frame members and the porcelain slab which recess surrounds the entire 80 outer and upper edges of the porcelain slab. 85

When the apparatus is assembled, the porcelain slab is placed against the hook-shaped member of the top frame portion when this portion is upside down. Cement 90 is then filled in all around the outer edge of the slab so that it completely surrounds this edge and the top edge as indicated at 7 in Fig. 5. The lower frame member is then placed against the bottom surface of the slab so that the lugs 4 and lugs 5 register. The screws 6 may then draw the two frame portions to bind the frame and slab together, and the cement which is provided in excess quantity in the recess will be forced 95 therein to fill the recess, surround the outer edge of the slab member 3, and extend over the edge of that member. The apparatus is then turned right side up, and, when whatever cement is squeezed out between the 100 upper frame member and the top surface of the slab is scraped away and the cement is hardened, the apparatus is ready for use.

The depending flange 10 and the upper 105 hook-shaped portion of the frame member 110

2, together with the top of the slab, presents an unbroken surface equivalent to the same surface on a molded article of one piece. The device thus assembled looks sanitary and is sanitary for use particularly where food is handled. It may readily be cleaned without any opportunity for foreign matter to enter crevices and holes.

It has heretofore been desired to provide a sanitary surface such as found on porcelain and analogous materials for handling foods, but considerable difficulty has been found in a suitably mounting such materials in a proper manner. The device shown herein makes such materials available in a novel and useful manner.

My invention is more particularly defined in the appended claim.

What I claim is—

- 20 A sanitary tray arm for a luncheon chair or the like, comprising, in combination, a lower closed loop frame having means formed on its under side to support it from a chair or the like and provided with 25 a flat upper supporting surface, a slab of porcelain or like washable material arranged to rest on said surface and be supported therefrom, an upper tray frame,

comprising, a closed loop arranged to fit over the lower frame and the slab to conceal the former and to form a smooth unbroken rounded rim around and above said slab, said frame being of substantially hook-shaped cross-section and formed with a short inner depending flange to rest on the slab and a longer outer depending flange to form a skirt to conceal the lower frame and protect the user from corners and rough edges, a series of lugs formed on the interior of said tray frame and depending therefrom, securing devices arranged to pass through the lower frame and into said lugs to draw the frames together to force the slab into engagement with the short inner depending flange on the tray frame, all constructed and arranged so that a recess is provided under the tray frame and around the top marginal portions and the side edges of the slab, and cement or the like filling said recess to form a closed water tight joint 50 between the frame and the top surface of the slab.

WILLIAM N. STACEY.
